TELEPHONE STAND

Filed Sept. 2, 1927

INVENTOR
J. L. SHAHAN
BY *Munro & Co.*
ATTORNEY

UNITED STATES PATENT OFFICE

JOHN L. SHAHAN, OF CHICAGO, ILLINOIS

TELEPHONE STAND

Application filed September 2, 1927. Serial No. 217,217.

My invention relates to improvements in telephone stands, and it consists in the combinations, constructions, and arrangements herein described and claimed.

An object of my invention is to provide a telephone stand which may be readily secured to any suitable support, such as a wall, for holding a telephone.

A further object of my invention is to provide a device of the type described which has novel means for receiving a plurality of coins or slugs.

A further object of my invention is to provide a device of the type described by means of which coins or slugs may be readily removed therefrom when desired.

Other objects and advantages will appear in the following specification, and the novel features of the invention will be particularly

pointed out in the appended claims.

My invention is illustrated in the accompanying drawings, forming part of this application, in which

Figure 1 is a side elevation of one form of my device,

Figure 2 is a section along the line 2—2 of Figure 1,

Figure 3 is a bottom plan view of a portion of the structure shown in Figure 1,

Figure 4 is a plan view of another form of my device, and

Figure 5 is a side elevation of that form shown in Figure 4.

In carrying out my invention, I provide a support 1 having a rim 2 disposed around the sides and front wall thereof. A brace 3 is rigidly secured to the support 1 and is arranged to be secured to an upright member, such as a wall, 4 by means of a screw 5. A retaining clip or bracket 6 is secured to the support 1 for receiving a screw 7 which is arranged to secure the clip or bracket 6 to the upright 4.

The support 1 is provided with an opening 8. A receptacle 9 is secured to the support 1 in communication with the opening 8. The receptacle 9 is provided with a circular opening 10 for receiving a plurality of coins indicated at 11. The receptacle 9 is provided with a stop member 12 which has a cutaway

portion or recess 13 for a purpose hereinafter described.

The form shown in Figures 4 and 5 consists of a support 1' having a rim 2' around the side and front walls thereof. A brace 3' is secured to the support 1' and arranged to be secured to an upright or wall 4' by means of screws 5'.

The support 1' is provided with an opening 8'. A receptacle 9' is secured to the support 1' in communication with the opening 8'. The receptacle 9' is provided with an opening 10' which is arranged to receive coins 11'. The lower portion of the receptacle 9' is provided with an integral stop member 12' having a cutaway portion or recess 13'. The brace 3' is provided with a recess 14' for receiving cards or memorandums.

From the foregoing description of the various parts of the device, the operation thereof may be readily understood. Let us assume that the devices are secured to the uprights or walls. The supports 1 and 1' may readily receive a telephone which when placed thereupon would cover the opening 8 or 8'. Coins or slugs may be dropped in the openings 8 and 8' and lodged in the receptacle 9 or 9' by raising the telephone. The coins or slugs may be removed singly by placing a finger within the cutaway portion 13 or 13' and moving the finger outwardly toward the outer extremity of the opening. The frictional contact of the finger is sufficient to move the lowermost coin or slug free from the remaining slugs or coins. In this way the user can readily receive a coin when making a call. The coins or slugs are hidden from view and are readily accessible.

I claim:

1. A device of the type described comprising a plate member having one edge adapted for being connected to a supporting member and the opposite edge provided with an enlarged portion having a passageway therethrough, said plate member being provided with an enlarged top portion, said top portion being provided with an opening therethrough in communication with said passageway.

2. A device of the type described comprising a plate member having an edge adapted for being connected with a vertical supporting member, the opposite edge being provided with a cylindrical formation having a vertical passageway therethrough, said plate member being provided with an enlarged top portion, said top portion being provided with an opening therethrough in registration with said vertical passageway, and a retaining plate connected with the bottom of said cylindrical portion and provided with an opening therethrough of less diameter than the passageway.
3. A device of the type described comprising a plate member having an edge adapted for being connected with a vertical supporting member, the opposite edge being provided with a cylindrical formation having a vertical passageway therethrough, said plate member being provided with an enlarged top portion, said top portion being provided with an opening therethrough in registration with said vertical passageway, and a retaining plate connected with the bottom of said cylindrical portion and provided with an opening therethrough of less diameter than the passageway, the bottom of said cylindrical portion being provided with a transverse outlet opening whereby an article disposed in said passageway may be withdrawn therefrom.
4. A device of the type described comprising a plate member having an edge adapted for being connected with a vertical supporting member, the opposite edge being provided with a cylindrical formation having a vertical passageway therethrough, said plate member being provided with an enlarged top portion, said top portion being provided with an opening therethrough in registration with said vertical passageway, and a retaining plate connected with the bottom of said cylindrical portion and provided with an opening therethrough of less diameter than the passageway, the bottom of said cylindrical portion being provided with a transverse outlet opening whereby an article disposed in said passageway may be withdrawn therefrom, the bottom of said plate member being provided with a cutaway portion whereby said article may be removed from the transverse opening.

JOHN L. SHAHAN.
